UNITED STATES PATENT OFFICE.

AUGUSTIN J. CHEVRETTE, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS.

WEFT DETECTOR FOR LOOMS.

Application filed June 18, 1925. Serial No. 38,072.

This invention relates to improvements in detecting mechanism for weft replenishing looms and an object of the invention is to provide a detector which shall be unaffected by the angular position of the bobbin in the shuttle.

In multi-color looms the weft detector is required to cooperate with two or more shuttles the springs of which may not hold the bobbins at the same angle. It is found that due to the inaccuracies of the bobbin springs the tips of some bobbins will be disposed rearwardly with respect to the axis of the shuttle while the tips of other bobbins will be forward of the shuttle axis. Under such conditions if the detector be set to leave a safe amount of yarn on a rearwardly disposed bobbin it will not be set properly for a bobbin which is disposed forwardly.

It is a further object of my invention to provide a pair of cooperating detectors of the yarn penetrating and side slipping type, the yarn penetrating members being spaced and each cooperating with a separate angularly movable toothed detector arranged to move longitudinally of the bobbin at weft exhaustion.

It is a still further object of the invention to provide a pair of detectors having side slipping elements to cooperate with the loom controller in such a way that if either element is held against indicating movement the controller will be prevented from indicating a transfer even though the other element is free to move.

With these and other objects in view which will appear as the description proceeds, my invention resides in the combination and arrangement of parts hereinafter described and set forth in the claims.

In the accompanying drawings wherein I have shown one convenient form of my invention,

Fig. 1 is a top plan view of a weft detector having my invention applied thereto,

Fig. 2 is a side elevation of the detector looking in the direction of arrow 2, Fig. 1,

Fig. 3 is a central vertical longitudinal

section on line 3—3 of Fig. 1, the parts 50 being in normal position,

Fig. 4 is a rear elevation of the detector looking in the direction of arrow 4, Figs. 2 and 3,

Fig. 5 is a horizontal section on line 5—5 of Fig. 4, showing the interior mechanism of the detector in normal nonindicating position,

Fig. 6 is similar to Fig. 5 showing the parts in indicating position, and

Figs. 7 and 8 are vertical sections on lines 7—7 and 8—8 respectively of Fig. 5.

Referring more particularly to the drawings it will be seen that I have provided a bracket 10 from which extends laterally 65 arm 11 in which is secured a stud 12. A feeler bed 13 is mounted on said stud and has mounted for longitudinal movement therein a slide 14 having upstanding therefrom a clip 15 (see Fig. 3). A cap 16 is 70 secured to the bed 13 and has mounted therein a stud 17 with an enlarged threaded head 18 received in the rear vertical wall of the cap. A spring 19 interposed between the forward wall of the cap and the clip 15 75 holds the latter against the head 18 of the stud and permits yielding forward motion of the slide.

Upstanding from the bracket 10 is a horn 20 which receives a rearwardly extending 80 loom controller 21 mounted on the upper end of an arm 22 secured to a shaft 23. Said shaft is rotatably mounted in arms 24 extending forwardly from the bracket 10 and is surrounded by a coil spring 25 85 interposed between a collar 26 secured to the shaft and one of the arms 24. Said spring 25 holds the rear end of the controller 21 normally under a floating actuating lever 27 which receives motion from a 90 vertically reciprocating block 28 and has connection with the replenishing mechanism (not shown) by means of a link 29. The shaft 23 has secured thereto an arm 30 normally positioned by a governor 31 and the parts are so arranged that the controller 21 95 will be moved from under the actuating lever 27 when the latter descends on a non-

indicating pick of the loom. On indicating picks, however, the governor 31 will remain stationary, as will also the arm 30, to permit the controller 21 to remain under the lever 27 and as the latter descends it will move about the controller 21 as a center to depress link 29 and give an indication of weft exhaustion to the replenishing mechanism. The mechanism thus far described is of common construction and for further description of the same reference may be had to Patents Nos. 972,772 and 1,030,748.

My improvements relate more particularly to the devices which control the position of the governor 31. In carrying out my invention I provide the slide 14 with a pair of yarn penetrating detectors 40 and 41, respectively, which may conveniently be formed on the ends of bars 42 extending between the upper and lower plates 43 of the slide 14. Extending between said plates is a screw and nut 44 on which are pivotally mounted lower and upper side slipping toothed detectors 45 and 46, respectively. The slide 14 has fixed thereto a partition or wall 47 which extends parallel to the plates 43 and between the bars 42 to separate said detectors 45 and 46 and guide the same in spaced parallel guideways. The detector 45 has extending to the left therefrom an arm 48 and the detector 46 has a similar arm 49, said arms being bent downwardly as indicated in Figs. 2 and 4.

Secured to the under side of the bed 13 is a stop 50 having oppositely extending fingers 51 which engage the arms 48 and 49 to hold the corresponding detectors against their penetrating detectors. Said stop 50 is provided with a slot 52 through which extends a holding screw 53 by means of which the position of said slide may be adjusted forwardly and rearwardly and said stop is guided to slide between bosses 53^a depending from the bed 13. As shown more particularly in Fig. 5 the rear end of the governor 31 is threaded into a head 54 having horns 55 which are spaced equally from the axis of the governor 31 and engage the depending portions of the arms 48 and 49, respectively, at points opposite the fingers 51. Blocks 56 are secured to the slide 14 and guide the governor 31 so that the horns 55 are always in alignment with arms 48 and 49. The rear face of lever 30 is slotted as 55 to receive the T-shaped end 58 of the governor and prevent rotation of the latter. The right hand horn 55 passes between the upper plate 43 of the slide and the adjacent side bar 42 to prevent rotation of the head. Under normal condition the spring 19 will hold the slide 14 rearwardly with the arms 48 and 49 against the fingers 51 so that pivoted detectors 45 and 46 are adjacent penetrating detectors 40 and 41, respectively. As a bobbin W supplied with suf-

ficient yarn for continued weaving is presented to the detector the forward surface thereof will engage the pivoted detectors 45 and 46, restraining pivotal motion thereof, and the slide 14 will be moved forwardly 70 carrying the governor therewith to move the controller 21 from under the lever 27. When insufficient yarn is present on the bobbin the penetrating detectors will engage the bobbin and move the slide 14 forwardly but 75 the pivoted detectors will be unresisted and therefore free to move angularly about the screw 44 under influence of the horns of the governor. The latter will therefore remain stationary and the controller will be 80 under lever 27 as it moves down. Should the front surface of the bobbin be disposed obliquely with respect to the slide 14 as shown at the dotted line 60 in Fig. 5 detectors 41 and 46 will not be engaged by the 85 bobbin and will therefore be free to move, but so long as sufficient yarn remains on a bobbin so disposed the detector 45 will be held against angular motion and arm 48 will press against the corresponding horn 55 90 and move the governor 31 forwardly to prevent indication of transfer. When indication of weft exhaustion is desirable penetrating detector 40 will be pushed forwardly 95 by the wood of the bobbin and detector 45 will be free to rotate, at which time indication of transfer will be given as previously described. Under these conditions a relatively large amount of waste will result, but if the mechanism were supplied with 100 detectors 41 and 45 only the bare bobbin would strike the swinging detector and prevent angular movement thereof. Should the bobbin be disposed in the opposite direction but obliquely with respect to the 105 slide as indicated at line 70 in Fig. 5 a similar condition will exist with pivoted detector 46 determining the time of operation of controller 21. The teeth of the pivoted detectors 45 and 46 are normally forward 110 of the line joining the tips of the penetrating detectors 40 and 41 and this position can be varied if desired by constructing screw 44 as shown in Patent No. 989,429.

From the foregoing it will be seen that if 115 the right hand pair of detectors only were employed a bobbin disposed as indicated by line 70 would have left thereon an undue amount of waste yarn while a bobbin disposed as indicated at line 60 would prevent angular motion of the detector 45 and thereby prevent indication. By using two pairs of detectors with the penetrating members separated as shown I am able to detect with equal accuracy on bobbins which are disposed obliquely in either direction with respect to the axis of the detector and said detector also operates properly when the bobbin is perpendicular to the axis of the detector. Also, it will be noted that if 120 125 130

either pivoted detector is restrained against lateral motion controller 21 will be moved to prevent indication of weft exhaustion even though the other detector be free to 5 move on its pivot. The oppositely extending horns of the governor head prevent angular motion of the same with respect to the slide 14 and the stop 51 is adjustable to move the pivoted detectors to their proper 10 normal position when the clip 15 is against the head 18 of the stud 17.

Having thus described my invention it will be apparent that changes and modifications may be made therein by those skilled 15 in the art without departing from the spirit and scope of the invention, and I do not wish to be limited to the details herein disclosed but what I claim is:

1. In a weft detector for looms, an actuator lever, a controller therefor, a slide movable under influence of the advancing bobbin, two pairs of detecting elements mounted on the slide, each pair capable of detecting independently of the other, and 25 means to change the position of the controller only at such times as both pairs of detectors have indicating movements.

2. In a weft detector for looms, an actuator lever, a controller therefor, a slide 30 movable under influence of the advancing bobbin, and a plurality of pairs of detecting elements carried by the slide, each pair being effective to detect presence of weft independently of the other pair, and a governor operatively connected to the pairs of 35 detectors and operable thereby to determine the position of the controller only at such times as both pairs of detectors have indicating movements.

4. In a weft detector for looms, an actuator lever, a controller therefor, a slide movable rectilinearly under influence of the advancing bobbin, a pair of spaced yarn 45 penetrating detectors carried by the slide, a pair of angularly movable detectors pivotally mounted on the slide, each pivoted detector cooperating with one of the yarn penetrating detectors to constitute a detecting unit, each unit being effective to detect 50 yarn presence independently of the other unit, and connections between said detectors and the controller to determine the position of the controller from either unit, said controller being operatively related to the actuator lever only at such times as both units have indicating movements.

5. In a weft detector for looms, an actuator lever, a controller therefor, a slide 55 movable rectilinearly under influence of the advancing bobbin, a yarn penetrating detector on each side of the slide, a laterally movable detector for each yarn penetrating detector pivoted to the slide, the penetrating and movable detectors constituting a plurality of detector units each effective to

detect presence of yarn independently of the other, and connections between said units and the controller to determine the position of the latter from either unit, said controller being operatively related to the actuator lever only at such times as both units have indicating movements. 70

5. In a weft detector for looms, an actuating lever, a controller therefor, a slide movable under influence of the advancing bobbin, a pair of spaced yarn penetrating detectors secured to the slide, a pair of angularly movable toothed detectors to contact with the yarn, one of said pivoted detectors cooperating with one of the yarn penetrating detectors to constitute a detecting unit, a common pivot for said angularly movable detectors, and connections from said detectors to the controller to prevent indication of weft exhaustion when either 80 of said angularly movable detectors is held against lateral motion. 75

6. In a weft detector for looms, an actuator lever, a controller therefor normally in operative position with respect to the actuator, a slide movable rectilinearly under influence of the advancing bobbin, a pair of spaced yarn penetrating detectors on the slide, a pivoted detector for each yarn penetrating detector mounted on the slide and movable laterally with respect thereto in the direction of the length of the bobbin, oppositely extending arms for the movable detectors, a governor having spaced horns to engage the arms and tending to move the pivoted detectors in the direction of the length of the bobbin as the slide moves forwardly, said governor being operatively connected with the controller and moving the latter to inoperative position when the pivoted detectors are held against movement with respect to the slide, said controller remaining in operative position when said pivoted detectors move laterally. 90 100 105

7. In a weft detector for looms, an actuator lever, a controller normally in operative position with respect thereto, a slide movable rectilinearly under influence of the advancing bobbin, a pair of spaced yarn penetrating detectors for the slide, a pair of laterally movable detectors on the slide, arms extending from said movable detectors in opposite directions, a fixed stop for the arms, yielding means to hold said slide toward the bobbin, a governor tending normally to hold the arms against the stop, and connections from the governor to the controller to move the latter to inoperative position when either movable detector is held against movement with respect to the slide, said governor and controller remaining in normal position when the movable detectors are free to move angularly with respect to the slide. 115 120 125

8. In a weft detector for looms, an actu-

ator lever, a controller therefor, two pairs of detecting units movable forwardly under influence of the advancing bobbin, each unit having a yarn penetrating element and a second element movable in the direction of the length of the bobbin at substantial exhaustion of weft, and means operatively connecting the controller and units to prevent indication of weft exhaustion unless both units have indicating movements.

9. In a weft detector for looms, an actuator lever, a controller therefor, two pairs of detecting units movable forwardly under influence of the advancing bobbin, each unit having a yarn penetrating element and a second element movable in the direction of the length of the bobbin at substantial exhaustion of weft, and means operatively connecting the controller and units to prevent indication of weft exhaustion unless

both of said second elements of each unit have an indicating movement in the direction of the length of the bobbin.

10. In a weft detector for looms, a regularly moving actuator lever, a controller therefor normally operatively positioned relatively thereto, two pairs of detecting units, each unit comprising a pivoted detector and a yarn penetrating detector cooperating therewith, and means to move said controller out of operative position relatively to the actuator lever when either detector unit indicates presence of weft and to leave said controller operatively related to the actuator lever at such times only as both units indicate absence of weft.

In testimony whereof I have hereunto affixed my signature.

AUGUSTIN J. CHEVRETTTE.
